CLAIM

The ornamental design for a “display mount,” substantially as shown and described.

DESCRIPTION

FIG. 1 is a front elevation view of a display mount, showing my new design;

FIG. 2 is a rear elevation view of the display mount of FIG. 1;

FIG. 3 is a first side elevation view of the display mount of FIG. 1;

FIG. 4 is a second side elevation view of the display mount of FIG. 1;

FIG. 5 is a bottom plan view of the display mount of FIG. 1;

FIG. 6 is a top plan view of the display mount of FIG. 1; and, FIG. 7 is a perspective view of the display mount of FIG. 1. The broken lines immediately adjacent to the claim and define broken line regions depict the bounds of the claimed design, while all other broken lines are directed to environment. The broken lines form no part of the claimed design. The “VIVO” lettering and icon forming part of the disclosure is a registered trademark of CKnapp Sales Inc.
